WORKPIECE MOUNTING AND TURNING UNIT
FOR SURFACE GRINDERS AND THE LIKE

Paul G. Nesteriak, Pearmain St., Shelton, Conn.

Filed Aug. 17, 1962, Ser. No. 71,342

Term of patent 14 years

(Cl. D54—6)

Fig. 1

Fig. 2

Fig. 3

*Fig. 4**Fig. 5**Fig. 6*FIGURE 1 is a front elevational view of a workpiece mounting and turning unit for surface grinders and the like embodying my new design.

FIGURE 2 is a left end elevational view thereof.

FIGURE 3 is a right end elevational view thereof.

FIGURE 4 is a rear elevational view thereof.

FIGURE 5 is a top plan view thereof; and

FIGURE 6 is a bottom plan view thereof.

I claim:

The ornamental design for a workpiece mounting and turning unit for surface grinders and the like, as shown.
